UNITED STATES PATENT OFFICE.

ERNESTO RICCIO, OF NEW YORK, N. Y.

HAT-RETAINER.

1,198,055.

Specification of Letters Patent. Patented Sept. 12, 1916.

Application filed June 5, 1916. Serial No. 101,745.

To all whom it may concern:

Be it known that I, ERNESTO RICCIO, a subject of the King of Italy, residing at New York, in the county of New York and 5 State of New York, have invented certain new and useful Improvements in Hat-Retainers, of which the following is a specification.

This invention relates to new and useful 10 improvements in hat retainer.

The primary object of the present invention is the provision of a retaining means positioned within a hat and adapted for ready manipulation exteriorly thereof for 15 engaging the hair of the wearer for retaining the hat in position, while the device may be worn as a hair ornament or barrette when detached from the hat.

A further object of the device is the provision of an arrangement positioned within 20 a hat provided with resiliently operating closing jaws retractable from a point outside of the hat by means presenting the appearance of ordinary hat pins having fanci- 25 ful heads imparting esthetic beauty to the device when operatively assembled.

With these general objects in view and others that will appear as the nature of the invention is better understood, the same consists 30 in the novel combination and arrangement of parts hereinafter fully described, illustrated in the accompanying drawing and then claimed.

In the drawing forming a part of this application and in which like designating characters refer to corresponding parts throughout the several views:—Figure 1 is a central radial sectional view through a hat provided with the present device, the latter arranged in its normal retaining position. Fig. 2 is a side elevational view of the device detached, parts being broken away, the elements being illustrated by dotted lines in their open position. Fig. 3 is 45 a bottom plan view of the device. Fig. 4 is a transverse sectional view thereof taken upon line IV—IV of Fig. 2, and Fig. 5 is a perspective view of an end portion of one of the operating rods with one of the anchors 50 for the spring member of the device mounted thereon.

It will be understood that the present invention may be employed with hats of different construction, the same being herein 55 illustrated as carried by a straw hat 10 having a crown 11 provided with a flat top 12,

the said hat having the usual outwardly projecting brim 13.

The device for retaining the hat in position upon the head of the wearer consists 60 of an elongated base plate 14 having depending end flanges 15 and intermediately arranged spaced bearing brackets 16. The plate 14 is provided with an oval central opening 17 and with a plurality of perforations 18 between the said brackets 16, adapted for receiving thread or other hold-fast devices (not shown) for securing the plate 14 to the inner side of the hat crown 12 in the position illustrated in Fig. 1 of the drawing. 70

Shifting blocks 19 of substantially the same size and shape as the brackets 16 are arranged outwardly thereof provided with operating rods 20 centrally secured to the blocks 19 by the threaded inner ends 21 of 75 the said rods, the latter being journaled through central perforations 22 in the end flanges 15. The rods 20 are in substantial axial alignment with each other and project outwardly through the hat crown 11 being 80 provided with heads 23 upon their outer ends conforming to any desired configuration of hat pin head thereby presenting a structure that is valuable for its esthetic beauty. The blocks 19 are provided with 85 spaced guide pins 24 projecting inwardly through guide openings 25 in the brackets 16, the inner ends 26 of the said pins being sharpened for entering the hair of the wearer when the hat 10 is positioned upon 90 the hat. Anchoring posts 27 are carried by the inner ends of the rods 20 for receiving thereover the opposite ends of a resilient member 28 such as an elastic band or tape, which resilient member freely passes 95 through alining perforations 29 and 30 in the brackets 16 and block 19 respectively, thus connecting the two blocks 19 resiliently together. The perforations 22 and 25 are preferably provided with bushings 31. 100

From this detailed description of the device, the complete operation thereof will be apparent. With the device secured in the hat 10 as illustrated in Fig. 1 of the drawing, the resilient member 28 normally holds 105 the blocks 19 in flat engagement with the brackets 16 and with the inner ends 26 of the pins 24 slightly spaced apart. Upon placing the hat 10 upon the head of the wearer, the heads 23 are grasped and the 110 rods 20 as well as the blocks 19 pulled outwardly, thus separating the pin ends 26 and

allowing some of the hair of the wearer to be positioned therebetween. Upon releasing the rod heads 23, the resilient member 28 draws the pins 24 toward each other and 5 engages some of the hair upon the pins 24, the ends 26 being forced through the hair. In this manner, the hat 10 is secured upon the head of the wearer and can only be removed by forcibly separating the pins 24 10 by pulling outwardly upon the rod heads 23.

The exterior appearance of the hat 10 when provided with this device is enhanced in beauty while the device consumes very little space and in no manner interferes with 15 the usual use of the hat.

This device may be separately employed as a barrette for holding the hair, having no connection with the hat when desired.

What I claim as new is:—

20 A device of the class described comprising a flat plate, projecting end flanges and intermediate spaced brackets carried by the said plate extending in the same direction,

shiftable rectangular blocks arranged between the said flanges and the adjacent 25 brackets, operating rods carried by said blocks and projecting outwardly through the said flanges, upright anchoring posts of eye-bolt construction having the circular portions carried by the said rods adjacent 30 the said blocks, the said blocks and brackets having alining perforations therethrough in the plane of the said posts, a resilient connector passing through the said block and bracket perforations with its opposite ends 35 secured to the upper ends of the eye-bolts, the said brackets being provided with openings adjacent the said perforations at opposite sides thereof and inwardly extending hair engaging pins carried by the said blocks 40 slidably extending through the said bracket openings, the said blocks and brackets adapted to lie in flat engagement when in operative position.

In testimony whereof I affix my signature. 45
ERNESTO RICCIO.
